TESTING TOOL FOR WELLS

Harold E. Dripps and Henry Rauser,
Lake Charles, La.

Application November 10, 1938, Serial No. 239,779

11 Claims. (Cl. 166—1)

This invention relates to well testing apparatus.

An object of the invention is to provide a well tester of the character described shaped to be

5 lowered into a well and having a sample chamber therein which is closed to prevent the entrance of the drilling fluid into the chamber while the tester is being lowered or withdrawn, the tool being provided with novel means for guarding 10 the sample chamber against the entrance of the drilling fluid at all times whereby to obtain an uncontaminated sample of the contents of the stratum being tested.

It is another object of the invention to provide 15 a well testing tool having a sample chamber therein, a suitable packer thereon for forming a seal between the tool and the walls of the well with a novel valve assembly for closing the chamber against the entrance of drilling fluid 20 from the well and novel means effective to open the valves of said assembly after the packer has been set, to permit the entrance of a sample from the stratum beneath the packer and to thereafter permit the valves to close to entrap 25 the sample.

The invention embodies a plurality of valves arranged, and operative in a novel manner to securely close the sample chamber and entrap the sample and to protect it from the entrance 30 of contaminating material.

The invention also embodies an equalizing valve arranged to be locked open when desired to permit by-passing of the drilling fluid while running the tool into the well or withdrawing it.

35 It is another object of the invention to provide a testing tool of the character described whose parts may be interlocked so that the tool may be rotated as a unit when desired, said parts having the necessary relative longitudinal movement for operating the equalizing valve as required.

The construction is such that while the tool is being lowered into the well the operating string may be moved up or down; or when the 45 packer is set on top of the rat hole it may be "spudded" to a firm seat, and the string and tool may be rotated, all without opening the valves guarding the sample chamber.

With the above and other objects in view the 50 invention has particular relation to certain novel features of construction, operation and arrangement of parts, an example of which is given in this specification and illustrated in the accompanying drawings, wherein—

Figures 1 and 2 show vertical, sectional views

of the upper and lower ends, respectively, of the tool showing the parts in the position they will occupy while the tool is being lowered into the well.

Figure 3 shows a side elevation, partly in section, of the complete tool.

Figures 4 and 5 show vertical, sectional views 10 of the upper and lower ends, respectively, of the tool as landed in home position preparatory to making the test.

Figure 6 shows a cross-sectional view taken on the line 6—6 of Figure 4.

Figure 7 shows a cross-sectional view taken on the line 7—7 of Figure 4.

Figure 8 shows a cross-sectional view taken 15 on the line 8—8 of Figure 4.

Figure 9 shows a cross-sectional view taken on the line 9—9 of Figure 5.

Figures 10 and 11 show vertical, sectional views 20 of the upper and lower ends of the tool with the valves open for permitting an inlet of the sample from the stratum being tested into the sample chamber.

Figure 12 is a cross-sectional view taken on the line 12—12 of Figure 2.

Referring now more particularly to the drawings wherein like numerals of reference designate the same parts in each of the figures, the numeral 1 designates, as a whole, a suitable packer. In the illustration shown this is a conventional type of rat hole packer adapted to be set at the upper end of the rat hole 2 as shown in Figure 5. It is to be understood, however, that any type of packer may be employed suitable to be set in a casing and expanded to 30 form a fluid tight joint therewith. As shown the packing element 1a is mounted on a tubular mandrel 3 to the lower end of which a perforated nipple 4 is connected by means of a clamp collar 5.

A main packer body 6 is connected to the upper end of the mandrel and the packer is tightly clamped between said body and the clamp collar 5. Attached to the upper end of the body 6 there is a by-pass valve housing 7 which is provided with the inside keyways 8, 8a extending from the lower end of the housing and terminating beneath the upper end thereof as more accurately shown in Figures 5 and 9.

Screwed into the upper end of the packer body there is a tubular by-pass valve seat 9 whose upper end is outwardly beveled. The upper end of the housing 7 has an internal, annular flange 10 which is spaced above the upper ends of the keyways 8, 8a.

A tubular nipple 11 is fitted upwardly through

the housing 7 and its lower end is outwardly flared so as to form a close fit with the upper end of the seat 9 thus forming a by-pass valve. The nipple 11 has the side keys 12, 12a adapted 5 to work in the keyways 8, 8a, the key 12 being of greater cross-sectional area than the keyway 8a. The housing 7 has the by-pass ports 13 therethrough. Beneath the flange 10 the housing 7 has an internal, annular groove 14 10 above the upper ends of the keyways 8, 8a. When the tool is assembled to run into the well the nipple 11 will be in its upper position, as shown in Figure 2, with the keys 12, 12a above the keyways 8, 8a and the nipple 11 turned so that the 15 keys 12, 12a will be out of registration with said keyways in which position they will rest on the bottom of the groove 14 and hold the by-pass valve open, as shown in said Figure 2, so that in going into a well filled with drilling fluid a portion 20 of the fluid beneath may pass up through the mandrel 3 and out through the ports 13. The key 12 will rest against the stop 7a as shown in Figure 12 so that while going in if the packer should turn, for any reason, the key 12 will pass 25 over the way 8a without entering it, and the stop 7a is set back so that the key 12a will pass by it; all to the end that the packer would have to turn completely around before the keys 12, 12a could register with their corresponding keyways 8, 8a and enter them to permit the by-pass, 30 or equalizing valve to close while going in. When the tool is set, ready for a test, the nipple 11 may be turned to register the keys 12, 12a with the keyways 8, 8a and the by-pass valve will be 35 closed when the tool is set down, as shown in Figure 5, that is, when the packer is set, for example, in the upper end of the rat hole and it is desired to make a test. This splined connection between the nipple 11 and the housing 7 also 40 permits the parts beneath to be rotated when necessary.

The upper end of the tubular nipple 11 is connected to the valve housing above by means of a coupling as 15. The valve housing consists of 45 the upper tubular jacket 16 and the lower, inwardly thickened, tubular casing 17 which have a screw threaded connection and the latter of which is screwed into the upper end of the coupling 15 and has a flow bean 18 screwed into the 50 lower end thereof and provided with the restricted passageway 19.

The numeral 20 designates an operating string of pipe such as a drill stem which extends to the ground surface. A tubular drive nipple 21 is connected to the lower end of the operating string 20 by a suitable coupling 22. The lower end of this drive nipple extends down into the upper end of the tubular jacket 16 and is provided with the side keys 23 which work in the inside vertical 55 keyways 24 in the jacket. A stuffing box embodying packing 25 and the compression gland 26 is provided at the upper end of the jacket around the drive nipple 21. The upper ends of the keyways 24 terminate beneath the stuffing 60 box forming the inside shoulders 27 which hang on the upper ends of the keys 23 when the tool is being lowered into the well or withdrawn. Screwed into the lower end of the drive nipple 21 there is a gland 28 whose upper end is beveled 65 on its inner edge forming a seat 29 and whose lower end has an external, annular flange 30 which is seated on the upper end of the main spring 31. The lower end of this spring is seated on an inside ring 32 which is screwed into the lower end of the housing 16 and into which ring

there is screwed the annular main valve seat 33 with which the downwardly opening main valve 34 cooperates to open and close said seat. This main valve 34 is screwed onto the lower end of the valve stem 35 which extends upwardly through the ring 32 and the gland 28 and whose upper end is enlarged forming a head 36 adapted to cooperate with the seat 29 on the upper end of the gland 28. The stem 35 has a passageway 37 extending throughout its length whose lower 10 end is closed by the valve 34 and whose upper end is open.

Around the stem 35 and located between the gland 28 and the ring 32 there is a floating spacing sleeve 39. Seated in the upper end of the drive 15 nipple 21 there is an inside cage 40 having an inside downwardly facing shoulder 41. Beneath this shoulder there are the downwardly converging locking dogs 42 whose upper ends are loosely attached to the cage and whose lower ends are 20 free and held inwardly by the bent pressure springs 43. Within the ring 32 and surrounding the stem 35 there is suitable packing 45 forming a seal with the stem and held in place by the seat 33. Above the valve 34 the stem is provided with 25 the downwardly diverging inlet ducts 46 which lead inwardly to the passageway 37.

The valve seat 34 is seated on the upper end of the coil spring 47 and this coil spring is seated on a plug 48 screwed into the upper end of the casing 17 and having the upwardly diverging ducts 49 which lead upwardly therethrough from the tapering valve seat 50. Cooperating with the valve seat 50 there is a downwardly opening valve 51 having a stem 52 which works through 30 an axial bearing in the plug 48. The upper end of this stem carries a suitable stop 53. Surrounding the stem 52 and interposed between the plug 48 and the stop 53 there is a coil spring 54 which normally holds the valve 51 in closed position. 35

The tool is assembled for entrance into the well, as shown in Figures 1 and 2, with the ports 13 open, as shown in Figure 2 and the key 12 resting against the stop 7a. As the tool is assembled it 45 should be partly filled with water so as to submerge the stem 35 the required depth for a reason to be hereinafter stated. As the tool is lowered the drilling fluid beneath may pass up around the packer 1 as well as up through the mandrel 50 3 and out through the ports 13 thus by-passing the drilling fluid and equalizing the pressure above and beneath the packer. Should the packer hang up in the bore hole for any reason, before bottom is reached, the operating string 55 may be elevated and lowered and the tool "spudded" downwardly without closing the equalizing valve seat 9 or opening the valves 34, 51. When the packer is set the entire tool may be rotated by turning the operating string until the 60 keys 12, 12a register with, and enter, the keyways 8, 8a; the keys 23, at all times working in the keyways 24.

Attention is called to the fact that the valve 34 is substantially fully opened before the valve 65 51 opens, upon downward movement of the string, and so remains open until after the valve 51 closes upon subsequent upward movement of the string. This is important for the reason that while the fluid is flowing upwardly, under pressure, the gritty substances therein will not so readily cut away the parts of the valve 34 and its seat as would be the case if said valve was only partly opened while the gritty fluid flowed therethrough. 70

While going into the well it will be noted that the valve 51 as well as the valve 34 are both closed to prevent entrance of drilling fluid into the sample chamber 55 above.

When the packer is seated and the test is ready to be made, the operating string is turned to align keys 12, 12a with their keyways and the operating string is let down, as shown in Figure 5, closing the valve seat 9 as indicated in Figure 5

- 10 and placing the spring 31 under compression as indicated in Figure 4. The spacing sleeve will now limit the relative downward movement of the operating string. The operating string may now be elevated so that the parts will assume the position shown in Figure 1 with the locking dogs 42 in their upper position. With the flow tube 56 in the apparatus these locking dogs will now be above the shoulder 44 on said flow tube. This flow tube 56 may be lowered through the operating string 20 and it will eventually land on the upper end of the stem 35 but its force will be broken by the liquid in the tool so that the force of the impact will not injure the tool or cause parting of the operating string. The flow tube 25 56 is an element of the tool itself and its insertion into operative position constitutes the final assembly of the completed tool. The operating string may then be lowered from the position shown in Figure 1 to the position shown in Figure 10 and the dogs 42 will engage the shoulder 44 on said tube and the flow tube will be forced downwardly against the upper end of the stem 35 moving said stem downwardly to the position shown in Figure 10 and opening the 30 valves 34 and 51. The fluid beneath the packer may then flow into the nipple 4 passing inwardly through the mandrel 3 and the nipple 11 and on up through the flow bean passing thence upwardly past the valve 51 through the ducts 49 and 46 35 and on up through the passageway 37 and through the flow tube 56 into the sample chamber 55. The flow bean 18 having the restricted passageway 19 there-through is necessary in case of strong well pressure to prevent the gritty fluid, flowing under strong pressure, from cutting out the parts of the tool.

After sufficient time has elapsed to permit the inflow of an adequate sample, the operating string may be elevated with the parts in the position indicated in Figures 1 and 2. As the operating string is elevated into the position shown in Figure 1 the springs 47, 54 will close the respective valves 34, 51 and the gland 28 will engage the head 36. The sample entrapped in the sample chamber 55 will thus be prevented from leaking out and drilling fluid will be prevented from entering and contaminating the sample.

It is to be noted that while going into the hole, or when the packer is seated, the valves 34 and 51 will not be opened by setting the weight of the string above down on the packer but will only be opened in response to the downward movement of the stem 35.

When the sample has been entrapped in the sample chamber the tool may be withdrawn from the well, the operating string being broken up in the usual way as the tool is withdrawn. While the tool is moving upwardly through the well which is filled with drilling fluid, the drill fluid above will readily pass around the packer 1 as well as through the ports 18 and through the valve seat 9, the mandrel 3 and the nipple 4 thus equalizing the pressure above and below the packer as the tool is being withdrawn.

What we claim is:

1. A testing tool for wells comprising a string of tubing; a packer and valve assembly carried by said string having an inlet passageway to establish communication with the interior of the string and having a packer to form a seal with the walls of the well, said assembly also having inlet valve means normally closing said passageway; a flow tube, means arranged to interlock said tube with the string whereby upon vertical movement of the string the tube will be actuated to open the inlet valve means.

2. A testing tool for wells comprising a string of tubing; a packer and valve assembly carried by said string having an inlet passageway to establish communication with the interior of the string and having a packer to form a seal with the walls of the well, said assembly also having inlet valve means normally closing said passageway; a flow tube, means arranged to interlock the string and tube whereby upon downward movement of the string the tube will be actuated to open the inlet valve means and means to close the inlet valve means upon upward movement of the string and flow tube.

3. A testing tool for wells comprising a string of tubing containing a sample chamber; a packer and valve assembly carried by the string having a packer adapted to seal off an area of the well bore, said assembly having a passageway leading from the sealed off area into the chamber and inlet valves normally closing the passageway; a flow tube adapted to be lowered through the string means arranged to connect the string to the tube whereby the tube will be actuated by downward movement of the string to open said valves and a liquid cushion in the chamber to cushion the impact incident to the landing of the flow tube.

4. A testing tool for wells comprising a string of tubing containing a sample chamber; a packer and valve assembly carried by the string having a packer adapted to seal off an area of the well bore, said assembly having a passageway leading from the sealed off area into the chamber and upper and lower valves normally closing the passageway; a flow tube adapted to be lowered through the string, means for operatively connecting the flow tube and string and effective to actuate the flow tube to open said inlet valves successively from above downwardly upon downward movement of the string.

5. A testing tool for wells comprising a string of tubing containing a sample chamber; a packer and valve assembly carried by the string having a packer adapted to seal off an area of the well bore, said assembly having a passageway leading from the sealed off area into the chamber and upper and lower valves normally closing the passageway; a flow tube in the string, means for operatively connecting the flow tube and string and effective to actuate the tube to open said inlet valves successively from above downwardly upon downward movement of the string and means to thereafter close the inlet valves upon the subsequent upward movement of the string.

6. A testing tool for wells comprising a string of tubing containing a sample chamber; a packer and valve assembly carried by the string having a packer adapted to seal off an area of the well bore, said assembly having a passageway leading from the sealed off area into the chamber and upper and lower, downwardly opening inlet valves normally closing the passageway; means for opening said valves upon downward movement of

- the string relative to the packer and valve assembly, said means including a flow tube in the apparatus with means carried by the string engageable with the flow tube and effective to move the flow tube downwardly upon downward movement of the string and means arranged to be actuated by said tube, upon such downward movement and effective to open said upper and lower valves successively from above downwardly upon such downward movement and means to thereafter close the inlet valves upon the subsequent upward movement of the string.
7. A testing tool for wells comprising a string of tubing containing a sample chamber; a packer and valve assembly carried by the string and having a packer adapted to seal off an area of the well bore, said string being movable vertically independent of said assembly, said assembly having a passageway leading from the sealed off area into the chamber and having downwardly opening valve means and means normally maintaining the valve means in position closing the passageway during such independent downward movement of the string, a flow tube in the string above the valve means, means arranged to interlock the flow tube with the string and in co-acting relation with the valve means and effective to open the valve means upon downward movement of the string.
8. A testing tool for wells comprising a string of tubing containing a simple chamber; a packer and valve assembly carried by the string and having a packer adapted to seal off an area of the well bore, said string being movable vertically independent of said assembly, said assembly having a passageway leading from the sealed off area into the chamber and having downwardly opening valve means and means normally maintaining the valve means in position closing the passageway during such independent downward movement of the string, a flow tube in the string above the valve means, means arranged to interlock the flow tube with the string and in co-acting relation with the valve means and effective to open the valve means upon downward movement of the string and means to close the valve

means upon subsequent upward movement of the string.

9. A testing tool for wells comprising a string of tubing containing a sample chamber; a packer and valve assembly carried by the string having a packer adapted to seal off an area of the well bore, said assembly having a passageway leading from the sealed off area into the chamber and inlet valves normally closing the passageway; a flow tube adapted to be lowered through the string and operatively connected with the valves and string and effective to open said valves upon downward movement of the string and a liquid cushion in the chamber to cushion the impact incident to the landing of the flow tube and means for closing the valves upon upward movement of the string.

10. In a testing tool for wells including a string of tubing having an inlet passageway to establish communication with the interior of the string and a packer to form a seal with the walls of the well; means for controlling said inlet passageway comprising a valve assembly including inlet valve means normally closing said passageway, a flow tube, means arranged to interlock said tube with the string whereby upon vertical movement of the string, the tube will be actuated to open the inlet valve means.

11. In a testing tool for wells including a string of tubing having an inlet passageway to establish communication with the interior of the string and a packer to form a seal with the walls of the well; means for controlling said inlet passageway comprising a valve assembly including inlet valve means normally closing said passageway, a flow tube adapted to be lowered through the string and operatively connected with the valves and string and effective to open said valves upon downward movement of the string and a liquid cushion in said string above the inlet valve to cushion the impact incident to the landing of the flow tube, and means for closing the valves upon upward movement of the string.

HAROLD E. DRIPPS. 45
HENRY RAUSER.
